CLAIM

The ornamental design for a finger-mounted teether simulative of lion, as shown and described.

DESCRIPTION

FIG. 1 is a top view of a finger-mounted teether simulative of lion showing my new design;

FIG. 2 is a left side view thereof;

FIG. 3 is a front view thereof;

FIG. 4 is a right side view thereof; and

FIG. 5 is a back view thereof; and,

FIG. 6 is a bottom view thereof.

In FIG. 6, the broken lines indicate the boundaries of the claim.
